UNITED STATES PATENT OFFICE

2,028,090

SUCTION CLEANER

Walter A. Frantz, Cleveland Heights, Ohio, assignor to The Apex Electrical Manufacturing Company, Cleveland, Ohio, a corporation of Ohio

Application December 13, 1929, Serial No. 413,825
Renewed March 26, 1934

24 Claims.

(Cl. 15—8)

This invention relates to vacuum cleaners and in particular to casings for portable vacuum cleaners.

Some of the structural features of the particular vacuum cleaner herein disclosed and used to illustrate one mode of practising my invention are shown in the French patent of Stanley McClatchie, No. 624,844, published July 27, 1927.

While my invention may be considered as an improvement of the McClatchie cleaner, it is furthermore adapted to be readily applied to various other types of vacuum cleaners as will be apparent to one skilled in the vacuum cleaner art upon examination of the disclosure of the following specification and appended drawing.

One of the objects of this invention is to provide a separable vacuum cleaner casing having a simple locking mechanism that may be readily fastened or unfastened to permit easy access to the interior of the casing and the operating parts of the cleaner.

Another object of this invention is to provide a two piece cleaner casing having hinged or interlocking sections to facilitate the opening and closing of the same.

A further object of this invention is to provide a vacuum cleaner having a motor driven brush with a two-piece casing so constructed and formed as to materially reduce the noise produced by the cleaner when in operation and at the same time permit the use of modern manufacturing methods in the fabrication of the casing and the assembly of cleaner parts.

Stated in general terms, my invention consists in the provision of a horizontally split two-piece cleaner casing, the lower half of which supports a revolving brush, motor and fan and the upper half of which forms a cover that engages or is hinged to the aforementioned lower half of the casing to provide a suction nozzle and an enclosure for the motor, fan and brush.

Important advantages result from the use of my improved two-piece cleaner casing. Manufacturing costs can be reduced, as the two halves of the casing can be made from die castings which process cuts down the cost of the original casting as well as the cost of finishing the same. The cleaner parts may be more easily assembled in the open casing and when in the hands of the user ready access to the interior of the casing is obtained for cleaning, oiling, repairing or adjusting the cleaner parts.

With the aforementioned and other objects in view, the invention consists in the features shown and disclosed in the following specifications and

accompanying drawing and particularly pointed out and defined in the appended claims.

In the drawing Fig. 1 is a side elevational view of a vacuum cleaner embodying my invention; Fig. 2 is an enlarged side elevational view of the cleaner shown in Fig. 1 with the cleaner casing in open position; Fig. 3 is a side elevational view of the cleaner with certain of its parts shown in section; Fig. 4 is a section taken on line 4—4 Fig. 3; Fig. 5 is a front elevational view of the cleaner with a portion of the cleaner nozzle broken away to show mounting of the carrier wheels and handle bail; Fig. 6 is a sectional view showing a modified arrangement for the interlocking of the upper and lower parts of the cleaner casing.

The cleaner shown in the drawing consists of a portable suction cleaner having a horizontally divided casing including an upper half 1 and a lower half 2, which are locked together by a suitable fastener 3. The cleaner is mounted on oversized wheels 4 which are of such size that it is not necessary to support the nozzle on separate casters as the large size of the cleaner wheels maintains a substantially constant clearance with the floor covering for the movement and engagement of the cleaner nozzle.

Attached to the rear end of the cleaner casing is a dust bag or filter 5 which is attached at its upper end to the handle 6. An electric extension cord 7, adapted to be supported on the handle 6 when not in use is in electrical connection with the wire 8 leading to the cleaner motor. The handle 6 is secured to the bail 9 which is in turn journaled to the lower half 2 of the cleaner casing. The lead wire 8 from the cleaner motor is provided with a separable connector 31 which is adapted to be inserted in a complementary connector supported in the lower part of cleaner handle 6 which is in electrical connection with the cord 7.

The cleaner motor consists of a suitable electric motor (not shown) carried in a dust and air tight housing 13 which is suitably supported in the lower half 2 of the cleaner casing. The cleaner motor is provided with a shaft 15 which forms at its outer end a belt pulley adapted to drive the brush 11 by means of the belt 16. Immediately adjacent the motor, the fan 14 is carried on the shaft 15 in order to provide the necessary suction for the cleaning operation.

The cleaner brush 11 is provided with suitable bearings (not shown) at its outer ends which are journaled on the non-rotating shaft 18 that is detachably carried in the slot 20 of the plate 19. The plates 19 are secured in the ends of the

cleaner nozzle in any suitable manner such as by rivets 21. Upon removal of the belt 16, the brush 17 may be readily removed or inserted in the cleaner nozzle. The two parts of the cleaner 5 casing are held together by means of a hinge 23 on the nozzle portion thereof and by a fastener which consists of a suitable clamp 11 carried on a ring 10 secured to the flexible strap 3. The opposite end of the strap 3 is secured to the other 10 side of the casing 2. The clamp 11 engages a projection 12 formed on the lower half of the casing.

The front portion of the lower and upper 15 halves of the casing are designed so as to form a suction nozzle and housing for the belt and the brush and its driving means. A closure cap 22 provides upon its removal an opening aligned with a corresponding opening adjacent the fan 14 for the attachment of the suction hose of a 20 hand tool when it is desired to clean furniture and other objects that it would not ordinarily be possible to clean without removing the cleaner from the floor.

The casing 13 of the driving motor is suitably 25 supported in electrical and sound insulating supports 24, 25 and 26 which may be made of rubber or any other suitable material. The supports 24 are held in the lower half of the casing by means of bolts or screws 21. The upper support 30 26 is adapted to project through an opening in the upper half 1 of the cleaner casing and to provide a sleeve for the reception of the lead wire 8 which is connected to the cleaner motor.

The nozzle portion of the two halves of the 35 cleaner casing are connected to each other by means of a suitable hinge 23 or by forming this portion of the two halves of the casing with an interlocking joint such as shown on Fig. 6, where the upper half 1 of the casing is provided with 40 a forwardly extending lip 29 which co-acts with the rearwardly extending flange 30 formed on the lower half 2 of the casing.

In the operation of the device, upon connecting the plug 32 of the cord 7 to a source of electrical current the motor drives the fan 14 and creates a suction in the front end or nozzle portion of the cleaner which communicates with a fan chamber formed by the casing immediately adjacent the fan. The fan chamber in turn 50 communicates with the rear of the casing which terminates in the neck 23 which is adapted for reception of the cleaner bag coupling 27.

Access to the interior of the cleaner casing 55 may be readily had by unfastening the clamp 11 and removing the bag coupling 27, whereupon the cleaner casing may be opened to the position shown in Fig. 2 exposing the working parts of the cleaner for oiling, cleaning, etc.

Furthermore, it is to be understood that the 60 particular form of vacuum cleaner shown and described and the particular procedure set forth, are presented for the purposes of explanation and illustration and that various modifications and procedure can be made without departing 65 from my invention as defined in the appended claims.

Having thus described my invention what I claim is:

1. A suction cleaner comprising, a motor, and 70 a fan and brush operatively associated therewith, and a casing having upper and lower halves meeting upon planes which coincide substantially with horizontal planes through the centers of said motor, fan and brush.

75 2. A suction cleaner comprising, a casing hav-

ing a collecting nozzle and a fan chamber and a motor, the shaft of said motor projecting through said fan chamber and having a belt pulley, a brush located in said nozzle and operatively connected to said belt pulley, said casing having the upper part of the nozzle separable from the lower part and connected thereto by a hinge, and means cooperating with said hinge to hold said parts together. 5

3. A suction cleaner comprising, a motor, and 10 a fan and brush operatively associated therewith, and a horizontally split two-piece casing having a lower part for supporting said brush and an upper part cooperating therewith to provide an inclosure for said brush, the parts of 15 said casing meeting on a plane which substantially includes the brush axis.

4. A suction cleaner comprising, a motor, a 20 casing forming a collecting nozzle, a fan chamber and a motor housing, the shaft of said motor 25 projecting through said fan chamber and having a belt pulley, a brush located in said nozzle and operatively connected to said belt pulley, said casing being made in two separable parts meeting along a line which is parallel to said motor 30 shaft, and connected together by a hinge, floor wheels carried by the lower part of said casing and supporting the same with said shaft substantially horizontal, and means cooperating with said hinge to hold said parts together. 35

5. A vacuum cleaner comprising, a horizontally arranged motor, a fan driven thereby, a rotatable brush, a shaft for said brush, driving connections between said motor and brush, a two-piece casing for inclosing said motor, fan, 40 brush, brush shaft and brush driving connections and for supporting said motor and said brush shaft, the sections of said casing cooperating to form a suction nozzle, a fan chamber, an air passageway around said motor and a discharge 45 outlet, such casing parts being arranged one behind the other in the order named, means for securing said brush shaft and said motor in said casing, a dust bag communicating with the discharge outlet of said casing, a coupling for detachably securing said bag to said casing adapted to encircle and grip the complementary portions of the casing at this point, and interfitting means provided on the nozzle forming portions of said casing for securing the casing halves to each 50 other at this point in a displaceable manner, and releasable means cooperating with said bag coupling for detachably securing the two sections of 55 said casing to each other at the rearward part of the cleaner, the sections of said casing being arranged for relative displacement upon the release of said last named means and the removal of said bag coupling whereby ready access 60 may be had to the interior of said casing and to the operating parts of the cleaner without disturbing said motor and brush shaft securing means.

6. A vacuum cleaner comprising, a motor, a fan driven thereby, a rotatable brush, a shaft for 65 said brush, a power transmission belt for connecting said motor to said brush for driving the latter, a longitudinally split two-piece casing comprising mating halves for inclosing the aforesaid operating elements, means for supporting said motor and brush shaft in said casing in a 70 manner so that the casing halves may be readily separated without reference to the said motor and brush shaft or the disturbance of their securing means, elastic dielectric members interposed between said motor and casing for pre- 75

- venting the transmission to said casing of electrical currents and sound producing vibrations, the complementary parts of said casing cooperating one with the other when united to provide an 5 air passageway comprising a suction nozzle, fan chamber and a discharge outlet; a dust bag, means including a bag coupling for detachably securing the casing parts to each other at a point adjacent to the discharge outlet, and interfitting casing.
- 10 means for securing the casing halves to each other in a displaceable manner at a point remote from the discharge outlet whereby the halves of said casing may be readily separated to permit access to the cleaner parts.
- 15 7. In a vacuum cleaner, a motor having a rotatable shaft, a fan carried by said shaft, a rotatable brush, power transmission means between said brush and the shaft of said motor, a sectional casing for inclosing and supporting the 20 aforesaid elements, the sections of said casing cooperating with each other to form a fan chamber, a suction nozzle and a discharge outlet communicating therewith, means for securing the sections of said casing together, a dust bag, a bag coupling therefor arranged for detachable securement to the portions of the casing sections forming the discharge outlet, and means cooperating with said bag coupling for securing the sections of said casing together in a manner to permit the 25 ready displacement of the sections of said casing.
8. In a vacuum cleaner, a motor having an operating shaft, a suction fan carried by the shaft of said motor, a rotatable brush, power transmission means between said brush and the 30 shaft of said motor, a sectional casing for inclosing and supporting the aforesaid parts, interfitting means for securing together the casing sections in assembled relation adapted to permit the ready separation of the casing sections for obtaining access to the elements inclosed in said 35 casing, the sections of said casing cooperating with each other to form a fan chamber, a suction nozzle and a discharge outlet communicating therewith, a dust bag, and a bag coupling therefor, the portions of the casing sections defining the discharge outlet being arranged for detachably receiving said bag coupling.
9. A vacuum cleaner comprising, a motor and fan unit having a driving shaft extending therefrom, a rotatable brush, driving connections between said brush and the extended shaft of said motor, support members for said brush, and a two-piece casing for inclosing and supporting the aforesaid parts comprising complementary sections 40 cooperating to form a suction nozzle, fan chamber and discharge passageway and outlet; a dust bag connected to said outlet, and means comprising a bag coupling for detachably securing the casing sections to each other at one end of the cleaner, and interfitting provisions joining the casing sections together in a displaceable manner at the opposite end of the cleaner whereby one of the halves of said casing may be readily displaced to permit access to the interior thereof.
- 60 10. A vacuum cleaner comprising, a suction fan, a motor therefor, a rotatable brush, brush supporting members, driving connections between said motor and brush, a casing for inclosing and supporting said fan, motor, brush, brush supporting members and brush driving connections comprising mating sections cooperating to form a suction nozzle, fan chamber and motor housing, means for securing said motor and said brush supporting members in said casing, a dust bag communicating with the outlet of said fan chamber
- 65 5. A vacuum cleaner comprising, a suction fan, a motor therefor, a rotatable brush, brush supporting members and brush driving connections between said motor and brush, a casing for inclosing and supporting said fan, motor, brush, brush supporting members and brush driving connections comprising mating sections cooperating to form a suction nozzle, fan chamber and discharge outlet; a dust bag and a coupling therefor detachably engaging the portions of the casing sections forming the discharge outlet for removably securing said bag in place, and means for securing the sections of said casing to each other in a displaceable manner to permit access to said fan, motor, brush and brush driving connections.
11. A vacuum cleaner comprising, a suction 10 fan, a motor therefor, a rotatable brush, brush supporting members and brush driving connections between said motor and brush, a casing for inclosing and supporting said fan, motor, brush and brush driving connections comprising mating sections cooperating to form a 15 suction nozzle, fan chamber and discharge outlet; a dust bag and a coupling therefor detachably engaging the portions of the casing sections forming the discharge outlet for removably securing said bag in place, and means for securing the sections of said casing to each other in a displaceable manner to permit access to said fan, motor, brush and brush driving connections.
12. A vacuum cleaner comprising, a motor, a 20 fan driven thereby, a rotatable brush, brush supporting members and brush driving connections between said motor and brush, and a sectional casing for inclosing and supporting said motor, fan, brush and brush driving connections having a single displaceable section for permitting access to all of the aforesaid elements 25 without disturbing their relative position or operative relation, and quickly detachable securement means for holding the sections of said casing in their assembled and operative position.
13. A vacuum cleaner comprising, a motor, a 30 fan driven thereby, a rotatable brush, brush supporting members and brush driving connections between said motor and brush, and a casing formed from a plurality of sections defining a suction nozzle, fan case and housing for inclosing and supporting the aforesaid elements, one of the sections of said casing being displaceable to permit access to said motor, fan, brush, and brush driving connections without disturbing their supporting connections with said 35 casing, and releasable securement means for holding the sections of said casing in their assembled and operative position.
14. In a vacuum cleaner, a sectional cleaner 40 casing comprising mating halves defining a suction nozzle, a fan case, motor housing and discharge outlet, interfitting means remote from the discharge outlet for securing the casing halves to each other; a motor, an associated suction fan, a revolving brush and power transmission means between said motor and brush all inclosed in and carried by said casing, a dust bag, and an associated bag coupling detachably engaging those portions of the cleaner casing which cooperate to define the discharge outlet of said casing for securing said bag to the discharge outlet of said 45 casing.
15. In a suction cleaner, a compartmental casing defining a fan case and a communicating suction chamber terminating in a suction nozzle having a downwardly presented working mouth, a fan in the fan case, and means for driving said fan, said casing being formed from a plurality of cooperating sections including upper and lower sections each forming in part at least the walls 50 of the fan case, suction chamber and suction nozzle, the nozzle forming portions of said upper and lower sections having juxtaposed edges located above the level of the working mouth of the suction nozzle whereby the lowermost edge portion 55
- 70
- 75

- of the upper casing section terminates above the level of the working mouth.
16. In a suction cleaner, a sectional casing defining a fan case and a communicating suction nozzle having a downwardly presented working mouth with horizontally extending lips defining the lowermost portion of the casing, said casing being formed from a plurality of cooperating casing parts with certain of said casing parts having juxtaposed edges located in vertically spaced substantially horizontal planes the lowermost of which traverses the suction nozzle at a point just above and adjacent to the working mouth thereof, one of said casing parts forming in part at least the section of the nozzle located below such plane as well as a part of the walls of the fan case, said casing parts also having other juxtaposed edges extending between the aforesaid horizontally disposed edges thereof.
17. In a suction cleaner, a sectional casing defining a fan case and a communicating suction nozzle having a thickened marginal portion forming a downwardly presented working mouth at the lowermost portion of the casing, said casing being formed from a plurality of cooperating casing parts having juxtaposed edges located in vertically spaced substantially horizontal planes the lowermost of which traverses the suction nozzle at a point just above the working mouth thereof, a fan in the fan case of said casing, a brush rotatably mounted in the nozzle of said casing, and an operative driving connection between said fan and brush, said casing having a displaceable wall part to permit easy access to the driving connection of said brush.
18. In a vacuum cleaner, a suction fan, a driving motor therefor, a brush, members for rotatably supporting said brush, driving connections between said motor and brush, and a sectionally constructed casing forming a suction nozzle, fan case and motor housing for inclosing and supporting the aforesaid cleaner elements, said casing comprising a unitary section forming in part at least the walls of the suction nozzle, fan case and motor housing and a readily displaceable casing section cooperating therewith and having interfitting means and quickly detachable means spaced therefrom for effecting the detachable securing of such section with respect to the first named casing section to permit access to said fan, brush and brush driving connections.
19. In a vacuum cleaner, a suction fan, a driving motor therefor, and a sectionally constructed casing forming a downwardly directed suction nozzle, fan case and motor housing for inclosing and supporting the aforesaid cleaner elements, said casing comprising a plurality of separate and individual sections including a unitary upper section having top, side and end walls defining in part at least the walls of the suction nozzle, fan case and motor housing and merging into each other to provide an unbroken exposed outer surface which may be readily polished, said upper section having provisions for the attachment in a readily displaceable manner of other of said sections whereby access may be had to the fan without first requiring the use of tools in separating the casing sections, the walls of the upper section having surfaces so disposed with respect to each other as to provide cavities in the interior of the section with non-reentrant sides whereby the said section may be formed with non-collapsible dies.
20. In a vacuum cleaner, a suction fan, a driving motor therefor, and a sectionally construct-
- ed casing forming a downwardly directed suction nozzle, fan case and motor housing for inclosing and supporting the aforesaid cleaner elements, said casing comprising a plurality of separate and individual sections including a unitary upper section having top, side and end walls defining in part at least the walls of the suction nozzle and fan case and merging into each other to provide an unbroken exposed outer surface which may be readily polished, said upper section having provisions for the attachment in a readily displaceable manner of other of said sections whereby access may be had to the fan without first requiring the use of tools in separating the casing sections, the walls of the upper section having surfaces so disposed with respect to each other as to provide cavities in the interior of the section with non-reentrant sides whereby the said section may be formed with non-collapsible dies.
21. In a suction cleaner, a sectional casing defining a fan case and a communicating suction chamber having a beaded marginal portion forming a downwardly presented working mouth, said casing being formed from a plurality of cooperating casing parts with certain of said casing parts having juxtaposed edges located in spaced substantially parallel planes one of which traverses the suction chamber at a point just above the working mouth thereof, one of said casing parts forming the working mouth of the cleaner and in part at least the walls of the suction chamber, and readily detachable securing means for such casing part whereby ready access may be had to the interior of the suction chamber.
22. A suction sweeper comprising, a casing formed from a plurality of cooperating sections defining a suction chamber, a fan case and motor housing, a fan in said fan case, a motor in said motor housing for driving said fan having a shaft projecting therefrom into the suction chamber, a rotatable brush in said suction chamber, driving connections in said suction chamber between said shaft and brush, and means for rotatably and removably supporting said brush in said suction chamber, said casing having a readily displaceable part hinged to the casing for permitting easy access to said brush and brush driving connections.
23. A vacuum cleaner comprising a suction fan, a rotatable brush, an electric motor, driving connections between said motor and said fan and brush, a casing for the housing of said motor, fan and brush, formed from a plurality of sections and defining the exterior walls of a suction nozzle, fan case and motor housing, one of the sections of said casing being of integral construction with a hollowed-out portion for accommodation of the motor and forming in part at least the walls of the suction nozzle, fan case and motor housing, means for supporting said motor, fan and brush from the hollowed-out section of said casing, the sections of said casing being displaceable one from the other without disturbing the attachment of said motor, fan and brush with respect to the hollowed-out section of said casing, and detachable securing means for holding the sections of said casing in their assembled and operative position.
24. A vacuum cleaner comprising a suction fan, a rotatable brush, an electric motor, driving connections between said motor and said fan and brush, a casing for the housing of said motor, fan and brush, formed from a plurality of

sections and defining the exterior walls of a suction nozzle, fan case and motor housing, one of the sections of said casing being of integral construction with a hollowed-out portion for accommodation of the motor and forming in part at least the walls of the suction nozzle, fan case and motor housing, means for supporting said motor, fan and brush from the hollowed-out section of said casing, the sections of said casing being displaceable one from the other with-

out disturbing the attachment of said motor, fan and brush with respect to the hollowed-out section of said casing, the mounting of said motor including resilient elements interposed between said motor and casing to provide a flexible mounting for the motor, and detachable security means for holding the sections of said casing in their assembled and operative position. 5
